David Kirk.

DAVID KIRK, OF ORLEANS, NEW YORK.

Letters Patent No. 86,166, dated January 26, 1869.

IMPROVEMENT IN MACHINERY FOR CLINCHING HORSE-SHOE NAILS.

The Schedule referred to in these Letters Patent and making part of the same.

To all whom it may concern:

Be it known that I, DAVID KIRK, of Orleans, in the county of Ontario, in the State of New York, have invented a new and useful Machine for the Purpose of Clinching Horse-Shoe Nails on the hoof of the horse with less expenditure of time and labor; and I do hereby declare that the following is a full, clear, and exact description of the construction and operation of the same, reference being had to the annexed drawing, making a part of this specification.

In the accompanying drawing—

A represents a bed-piece, supporting two upright stanchions, B B, and a joint, G, having also attached a handle, K.

The stanchions B B have hung between them, by the pivot I, a half cog-wheel, forming part of a lever, C.

This half cog-wheel intersects with the cogs on the circular inclined plane, forming the upper part of an eccentric, D.

This eccentric is joined with a second lever, F, at the joint P, the lever F being attached to the bed-piece by the pivot L, through the joint G.

This lever F has also a steel clincher, E, attached, the face of which is covered with rasp-like teeth.

A spring, H, secured to the bed-piece A by a bolt,

of which the joint G forms the head, supports the lever F, likewise the eccentric, D, and holds in position the cogs on the inclined plane and the half cog-wheel of the lever C.

In the operation of the machine, the operator, supporting the foot and hoof of the horse by his knee, grasps the handle K with his left hand, the machine toward his own person, raises the lever C with his right hand, thereby permitting the spring H to raise the lever F to a requisite height, and places the projecting part of the bed-piece A under the shoe and bottom of the horse-hoof, the clincher E on the top of the hoof, and above the protruding nail to be clinched. The lever C is then lowered, the clincher E descends, pressing the nail into the hoof, and rasping off the surface, in its descent. This process is repeated till the nails in each shoe are clinched on the hoof.

What I claim as my invention, and desire to secure by Letters Patent, is—

The machine constructed and arranged to operate as hereinbefore described.

DAVID KIRK.
